UNITED STATES PATENT OFFICE.

WILLIAM C. GAMBLE, OF NEW YORK, N. Y., ASSIGNOR TO GENERAL OPTICAL COMPANY, INC., A CORPORATION OF NEW YORK.

CONTAINER FOR FUSED-BIFOCAL-LENS BLANKS.

Application filed January 27, 1925. Serial No. 5,010

Fused bifocal lenses are composed of two kinds of glass of different indices of refraction, a relatively small button or segment of flint glass commonly being fused into a depression or countersink in a major piece of crown glass to constitute the reading or near field. The rough blanks are made by forming a major blank of the crown glass and grinding and polishing the depression or countersink in its convex face if it be of perisopic form, preparing a flint glass button by grinding and polishing one face to fit into the depression or countersink and then subjecting the two pieces of glass to heat until they become fused together. Sometimes the manufacturer sells these rough blanks to the trade in that form and the dispensing optician or refractionist attends to having it ground down and finished to the proper surface curvatures. Sometimes the manufacturer finishes the blank on the bifocal side and sells it to the trade in that form, the optician having then only to finish the opposite side of the blank according to the prescription and cut and edge the product to make the finished lens. Such a blank is known as a semi-finished blank. Sometimes, although to a lesser extent, the manufacturer is called upon to finish both sides of the blank, leaving it only to the optician to attend to having the lens cut and edged. Such uncut but surfaced lenses have, of course, the same diametral dimensions as the rough blank and as the semi-finished blank. In applying the term "blank" herein, both in the specification and claims, I therefore desire to have it understood that I comprehend any one of the three forms above referred to which precede the cutting and edging of the finished lens, namely, the rough blank, the semi-finished blank, and the fully surfaced but uncut lens.

The optician will examine the blank for defects preliminary to doing any work upon it himself, because if there is some defect in the blank which makes it unusable for finishing into a lens, any work which the optician may perform upon the blank will be wasted. The optician, therefore, commonly subjects the blank to a very careful scrutiny and the principal point of inspection is the contact surface between the flint button and the depression or countersink in the crown glass. This surface is very often defective for one reason or another, and the most usual cause for a defect in this particular is the entrap-

ping of gas during the fusing operation, which causes bubbles in the contact surface. These bubbles interfere with the transmission of light and if they are sufficiently large or numerous, they render the blank worthless. Frequently, also, the flint button or segment is improperly placed, due either to a slipping of the button while fusing, or to an incorrect location of the button in the countersink before the blank is placed in the fusing oven. The blank must, therefore, be inspected as to the disposition of the segment. The optician will also want to measure the diameter of the segment, particularly in the semi-finished blank or in the surfaced but uncut lens, for it will be understood that if the bifocal surface is finished down too far, the segment will become too small.

These blanks have heretofore been sold in individual one-piece wrappers which are small folded cardboard boxes or cartons, glued along one side and having their ends closed by flaps. These cartons collapse to a flat condition when they are empty and the ends are open. The blank is wrapped in soft paper before being placed in the carton. In order to inspect a blank shipped in such a container, it is necessary for the optician to open one end of the box and take out the blank and the paper in which it is wrapped, remove the paper and then handle the blank itself during the examination. Under such circumstances the finished surfaces are liable to become scratched during the inspection. Furthermore a dealer when he receives a quantity of blanks usually inspects them all in order to be able to replace at once any which are defective and he is required, therefore, not only to take the blanks out of the boxes but to put them back again after the inspection.

The purpose of my invention is to provide a box or carton for such blanks which will facilitate the examination or inspection of the blanks and which will make it unnecessary for the blanks to be handled or removed from their boxes or containers during the examination. In accordance with my invention, I accomplish this by providing a shallow, open-top box of just the right size to take the blank with a snug fit, and I provide in the bottom of this box a hole with which the segment of the blank will register so that the contact surface may be examined by transmitted light without removing the

blank from the box. Notches are provided in the sides of the box to receive and properly locate a millimeter rule to measure the diameter of the segment of the semi-finished blank, the notches being in line with the center of the segment when the segment registers with the hole in the bottom of the box and the depth of the notches being such that the rule will not touch the finished surface of the blank. A sliding cover is provided for the box, and for the purpose of examination, it is only necessary to pull the cover back far enough to expose the segment. Preferably the cover is tubular in form and surrounds the box, thus covering the hole in the bottom of the box as well as the open top of the box. The blank fits so tightly in the box that there is no likelihood of its falling out during the examination. There is no occasion, therefore, to touch the blank with the hands or with any instrument during an inspection.

In the drawing I have illustrated one way in which my invention may be embodied, Figure 1 being a plan of the container open to inspection position, the cover being shown partially in section, and Figure 2 being a central section of the same with the cover in closed position.

The blank 1 is shown as round which is the shape in which they are most commonly made, and the box is substantially square, the blank fitting into it tightly. The box may be made of paper, wood, or other suitable material. In the bottom 2 of the box there is provided the segment-examination hole 3, which is somewhat larger than the segment 4 of the blank, the diameter being preferably about one-half the length of the side of the box. This hole 3 is near the side 5 of the box, and since the segment is near one edge of the blank, the segment will register with the hole 3 when the blank is placed in the box with the segment adjacent the side 5. Because of the tight fit of the blank in the box it will stay in this position when once it is placed there.

To facilitate the measurement of the segment 4, notches 6 are provided in the sides 7 and 8 of the box and the bottoms of these notches are substantially in line with the center of the segment. A millimeter rule when placed in these notches will, therefore, coincide with a diametral line of the segment. The center of the segment is somewhat below or outside of the center of the examination hole 3, as a result of which all except the very outside portion of the segment may be freely inspected under transmitted light. In the cutting out of the finished lens, this lower part of the segment is cut away and hence its examination is unimportant. The blank which is shown in the drawings is a semi-finished blank, the bifocal surface being finished to its final form. The height of the sides of the box is so proportioned that the

bottom of the notches 6 is above the surface of the blank, with the result that the millimeter rule will not touch the surface of the blank.

The cover 9 of the box slides toward and from the side 5 so that it may be pulled back just far enough to uncover the segment and the examination opening in the bottom of the box and thereby permit an inspection of the lens without entirely removing the cover from the box, this examination position being the one shown in Figure 1. The cover is preferably tubular in form as shown in the drawings so as to completely surround the box and thereby cover up the opening 3 in the bottom of the box, as well as to cover the top 80 of the box. This cover fits over the box with sufficient snugness that it will be frictionally retained in any position, such as shown in Fig. 1 and in Fig. 2.

It will be understood that in order to examine a blank in the box, it is only necessary to push the box out from the cover until it occupies substantially the position shown in Figure 1, when the segment may be placed over a source of light which will shine 90 through it by reason of the presence of the hole 3 in the bottom of the box. A magnifying glass is then used to inspect the contact surface under the strong transmitted light and any defects therein may be readily observed. If the contact surface is found to be all right, the optician will then place a millimeter rule in the notches 6 and observe the diameter of the segment. The examination is then complete and he has only to push the box back into the cover to its closed position, the inspection being thus performed without removal of the blank from the box or handling of the blank in any way. Thus the container at all times forms a holder for the lens blank by which the lens blank may be handled without touching it and by which it is at all times protected against injury.

It is obvious that various modifications may be made in the details and arrangement of parts herein described and illustrated for the purpose of explaining the nature of the invention, by those skilled in the art within the principle and scope of the invention as expressed in the appended claims.

I claim:

1. The combination of a shallow, substantially square, open-top box having in its bottom and near one side a circular light-transmitting blank-inspecting hole the diameter of which is approximately half the length of a side of the box, a fused bifocal lens blank fitting snugly in the box and frictionally gripped and held by the four sides thereof, such lens blank having its segment of smaller diameter than and in register with the said hole, and a sliding cover for the box slidable completely thereover in a direction normal to the side of the box near which the said hole is disposed.

2. The combination of a shallow, substantially square, open-top box having in its bottom and near one side a hole the diameter of which is approximately half the length of a side of the box, a fused bifocal lens blank fitting snugly in the box, and having a segment somewhat smaller than the said hole with its center outside that of the hole, the two sides of the box which are equidistant to the hole being notched on a transverse line substantially coinciding with the center of the segment when the segment is over the hole and the bottom of the notches being in a line above the upper surface of the blank, and a sliding cover for the box slidable thereover in a direction normal to the side of the box near which the said hole is disposed.
3. A container comprising a tubular frame member adapted to surround and support a single lens blank and having notches on opposite sides thereof adapted to the insertion of a scale, the bottoms thereof being above the lens surface at the line thereof, a bottom member attached thereto at one side thereof for the further support of the lens blank, means comprising an opening therein smaller than an average finger diameter, for the viewing and illumination of the blank while provid-

ing protection therefor, and means for the further protection thereof comprising a sleeve member adapted to cover the top, bottom and sides thereof.

4. An article of manufacture comprising a lens blank, and means for protecting and holding the lens blank comprising a frame part diametrically surrounding and frictionally gripping the lens blank, a blank-supporting bottom fixed to said frame part and provided with a light-transmitting blank-inspecting aperture, and a protecting cover sleeve frictionally slidable on the frame part and its bottom to close the top of the frame part and the aperture in the bottom.

5. The invention defined in claim 4, in which the said frame part is of sufficient depth that its top edges extend above the lens blank and in which such edges at the opposite sides of the said bottom aperture are each provided with a notch with the bottoms of these notches in a line above the upper surface of the lens blank for receiving a scale without the latter coming into contact with the lens blank.

In witness whereof, I hereunto subscribe my signature.

WILLIAM C. GAMBLE.
